RELEASEABLE TONE ARM LOCKING MEANS

Julius L. Giovannucci, North Haven, Conn., assignor to The Soundscriber Corporation, New Haven, Conn., a corporation of Connecticut

Application November 18, 1944, Serial No. 564,054

5 Claims. (Cl. 274—1)

1

This invention relates to sound recording and reproducing, and more particularly to an apparatus which is especially adapted for use as a dictating machine.

One object is to provide a machine of the above nature having recording and playback heads, both of which have forwardly-extending handles, to facilitate the raising and the lowering of said heads from the disk record upon which they are supported; and also to permit said heads to be easily swung laterally across said record.

Another object is to provide an apparatus of the above nature in which the handles of the recording and playback heads are embraced by a rigid inverted U-shaped clamping frame which also carries a pair of U-shaped cam members for clamping said handles securely in raised position whenever desired.

A further object is to provide a device of the above nature having a control lever protruding through the front of the chassis plate for controlling the speed of the turntable.

A further object is to provide an apparatus of the above nature in which mechanism is furnished whereby the operation of depressing the handle of the recording head clamping cam will automatically preset the control lever to full speed position.

A still further object is to provide an apparatus of the above nature in which the recording head clamping cam has a bell crank handle connected with a downwardly inclined strap for operating the recording-playback selector switch, and also having means to preset the turntable control lever.

A further object is to provide an apparatus of the above nature in which provision is made of a variable resistor coupled mechanically to the speed control lever and arranged in the input circuit of the amplifier in such a manner that a constant output volume will be maintained during playback regardless of the speed of the turntable.

A further object is to provide an apparatus of the above nature in which means are provided for adjusting the maximum playback speed at which the control lever may be preset.

A further object is to provide an apparatus of the above nature which will be relatively simple in construction, inexpensive to manufacture, easy to install and manipulate, compact, and very efficient and durable in use.

With these and other objects in view, there has been illustrated on the accompanying draw-

2

ings, one form in which the invention may conveniently be embodied in practice.

In the drawings:

Fig. 1 represents a perspective view of the dictating machine as it appears when both the recording and playback heads are clamped in raised position above the disk record.

Fig. 2 is a fragmentary plan view of the right hand front corner of the same, with the top of the cabinet removed.

Fig. 3 is a perspective schematic view showing the speed control and volume control mechanisms and also the mechanism operatively connected with the recording head clamping cam for restoring the control lever to the full speed position when the recording head is lowered upon the record.

Fig. 4 is a detailed sectional view of the supporting bracket for the speed control lever and volume control mechanism and associated parts.

Fig. 5 is a circuit diagram of a portion of the apparatus.

Fig. 6 is a front view of the upper portion of the apparatus showing the recording head clamping cam in lowered position, and the playback head clamping cam in raised position.

Fig. 7 is a perspective view of the recording head clamping cam.

Fig. 8 is a side view of the recording head and 30 the swinging arm upon which it is supported.

Fig. 9 is a side view of the playback head and its swinging arm.

Referring now to the drawings in which like reference numerals denote corresponding parts throughout the several views, the numeral 10 indicates a U-shaped head-supporting bridge which is secured to the opposite sides of a chassis plate 35 located in the upper part of a cabinet C by means of two pairs of screws 10a, 10a.

Mounted upon the bridge 10 is a U-shaped clamping cam 11 for holding a recording head RH in raised position above a record R. A similar U-shaped clamping cam 11a is furnished for holding the playback head PBH in raised position.

45 The depending arms of the cams 11 and 11a are pivoted on a common horizontal central pin 11b and a pair of outer horizontal pins 11c, 11d, respectively, which pins are mounted in a central depending lug 11e and the outer portions of said bridge 10, respectively. The recording head clamping cam 11 has a bell crank handle 12 at its right hand end provided with a downwardly offset horizontal rear leg 13 which is connected by a downwardly inclined strap 14 and 50 shoulder screws 15, 16 to a selector switch lever 55

block 18, said strap 14 passing through a slot 36 in the chassis plate.

The strap 14 has a slot 17 at its lower end for loosely embracing the screw 16 which extends from the side of the selector switch block 18, the latter also having a rearwardly-extending horizontal shaft 19 connected with a selector switch (not shown). The playback head cam 11a is also provided with a forwardly-extending handle 12a (see Figs. 1 and 6).

In order to restore the turntable to normal full speed whenever the recording head RH is lowered upon the record, provision is made of an inclined laterally-extending stud 20 connected to the intermediate portion of the strap 14, said stud being adapted to engage a rearwardly inclined upwardly-extending link 21 which is adjustably secured by means of a pair of screws 22, 23 to a channel-shaped bracket 25. The screw 22 serves as a pivot for the link 21, while the screw 23 is located in an arcuate slot 24 formed at the lower end of the adjustable link 21.

Below the bracket 25 provision is also made of a horizontal plate 26 which is connected by a screw 27 to the bracket 25 and forms a bearing for a stud shaft 28 which projects downwardly therethrough. As will be seen in Fig. 3, the bracket 25 is so disposed as to support the link 21 in laterally offset relationship to the axis of the stud shaft 28.

The stud shaft 28 is surrounded at its upper portion by a vertical bushing 29 which is journaled in a flat block 30 underlying the plate 26. The block 30 is attached rigidly, by means not shown, to a horizontal mounting plate 31.

In order to adjust the speed of the turntable T during playback, provision is made of an L-T shaped lever 32, the upper vertical end 33 of which passes through an arcuate slot 34 in the forward part of the chassis plate 35. The lever 32 is secured at the rear end to the top of the bracket 25.

The speed of the motor is controlled by a swinging magnet assembly 37 which is secured to the stud shaft 28 by means of a pair of horizontal set screws 38, 39, said magnet assembly being held upon said shaft 28 by an elastic fiber stop nut 40 located on the lower end thereof. The magnet assembly 37 has an air gap 41 which is adapted to embrace a magnetic brake disk 42 which is fastened to a turntable motor shaft 43 by means of a set screw 44.

It will be understood that by shifting the vertical end 33 of the speed control lever 32 within its slot 34, the magnet assembly 37 will be moved in an arc around the stud shaft 28 so that the air gap 41 will be either partially over, completely over, or outside the perimeter of the non-magnetic brake disk 42. By means of this construction the magnetic flux which passes through the gap 41 will be varied to increase or decrease the speed of the turntable T mounted on the motor shaft 43 in accordance with the area of the disk 42 which is actually embraced by said gap.

The volume of the playback will be automatically maintained at a uniform level by means of a movable resistor arm 45 located in a circular casing 45aa and mounted on a depending threaded shaft 46 which is located within an angle bracket 47 secured to said shaft 46 by a pair of nuts 48, 49 situated above and below said bracket 47 respectively. The shaft 46 has an unthreaded reduced lower section 50 secured as by a set screw 51 to a collar member 52 resting upon the adaptor plate 26. The vertical leg of the angle bracket

47 is secured to the bushing block 30 by means of a pair of horizontal screws 53, 54.

The arm 45 is mounted to swing over an arcuate resistance 45a connected at its ends to wires 45b, 45c leading to the output of a preamplifier P. The wire 45b and the arm 45 are connected to the input of a main amplifier A. By means of this construction it will be seen that as the speed control lever 32 is swung about the stud shaft 28 to reduce the speed of the turntable T during playback the volume of the amplifier A will be increased automatically by the resistor arm 45.

The recording and playback heads RH and PBH are pivotally mounted upon recording and playback arms 55 and 56, respectively, and have pivoted lifting handles 57, 58, respectively, on their forward ends. The handles 51, 58 have resilient and depending curved rear ends 59, 60 which are adapted to slidably engage the heads RH and PBH respectively.

Operation

When the cam handle 12 is swung upwardly, the U-shaped cam 11 will clamp the lifting handle 57 against the bridge 10 so that the recording head RH will be held and locked in raised position. Similarly, when the handle 12a is moved upwardly, the playback head PBH will be clamped in raised position.

It will be understood that the operation of lifting the handle 12 will swing the selector switch block 18 about its shaft 19 and place the apparatus in condition for playback. When the handle 12 is lowered again, the selector switch will be reversed to place the apparatus in condition for recording and the inclined stud 20 will engage the link 21 with a cam action and will force said link, the channel member 25, the plate 26 and the lever 32 to swing around the axis of the shaft 28, causing the control lever 33 to move to the end of the slot 34. The speed control lever 32 will thus be automatically restored to "full speed" position even though said lever may have been manually set for some lower speed.

It will also be understood that while the recording head is in raised position, the speed control lever 32 may be moved backwardly to cause the turntable to rotate at any lower playback speed without releasing the recording head clamping cam handle 12 from its raised position.

In case it is desired to adjust the position of the strap 14 to control the maximum turntable speed at which the apparatus may be preset, this may be accomplished by loosening the screws 22, 23 and swinging the link 21 to the desired angular setting after which the screws will again be tightened.

One advantage of the present invention is that both the recording head and the reproducing head of the dictating machine may selectively be moved to and held in any desired position upon the record R merely by manipulating the handles 51, 58 and 12, 12a and without touching the recording or playback heads themselves in any manner.

Another advantage of the present invention is that playback speeds as low as 2½ R. P. M. may be employed satisfactorily for playing back high speed code signals.

A further advantage is that the swinging of the U-shaped smooth-surfaced clamping cams will in no way injure the recording or playback heads or their handles.

While there has been disclosed in this specification one form in which this invention may be

embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new and for which it is desired to secure Letters Patent, is:

1. In a dictating apparatus, a phonograph chassis, a record-carrying turntable mounted in said chassis, a stylus-carrying head mounted to swing across said record, said head having a forward manipulating handle arm, a fixed horizontal bridge located above said arm, a clamping cam located below said arm and being pivotally mounted in said bridge, and means for swinging said cam upwardly into engagement with said arm to detachably lock said arm against said bridge in raised position above said record.

2. In a dictating apparatus, a phonograph chassis, a record-supporting turntable mounted in said chassis, a stylus-carrying head mounted to swing over said record, said head having a manipulating handle extending forwardly therefrom, a U-shaped bridge on said chassis and embracing said handle, a U-shaped clamping cam pivotally mounted in said bridge beneath said handle, said clamping cam having a handle to permit said cam to be swung upwardly into engagement with said head handle to detachably lock said head in raised position above said record and hold it from swinging movement.

3. In a dictating apparatus, a phonograph chassis, a record-supporting turntable and a driving motor therefor mounted in said chassis, a recording head mounted to swing over said turntable, a forwardly-extending manipulating handle on said head, a bridge of inverted

U-shape secured to said chassis and embracing said handle, a pivoted horizontal manually operable cam for raising and clamping said handle against said bridge, manually operable means for adjusting the speed of said motor during a playback operation, and mechanism connected to said cam for automatically setting said adjusting means at a predetermined point when said cam is moved to lower said recording head handle, whereby the turntable will rotate at a predetermined speed during every recording operation.

10 4. An apparatus as defined in claim 3, in which provision is made of a playback device, means for maintaining the playback volume at a uniform level regardless of the speed of said turntable, and means connecting said volume maintaining means for operation by said motor speed adjusting means.

15 5. An apparatus as defined in claim 3, in which said speed adjusting means includes a pivotally mounted magnetic brake for said motor, and setting mechanism comprising an inclined strap connected at its upper end to the recording head clamping cam, and means on an intermediate portion of said strap for engaging said speed adjusting means to reset said turntable to full speed when said cam is moved to released position.

20 30 JULIUS L. GIOVANNUCCI.
